UNITED STATES PATENT OFFICE.

FREDERICK HALDEMAN, OF CANTON, OHIO.

WINDOW-LOCK.

1,337,513.

Specification of Letters Patent. Patented Apr. 20, 1920.

Application filed October 8, 1919. Serial No. 323,944.

To all whom it may concern:

Be it known that I, FREDERICK HALDEMAN, a citizen of the United States, residing at Canton, in the county of Stark and State 5 of Ohio, have invented a new and useful Window-Lock, of which the following is a specification.

This invention relates to improvements in locks and more particularly to a lock 10 adaptable for use upon cellar windows such as are provided for filling a coal bin from the outside.

The objects of the invention are to provide a lock of this character which will 15 automatically lock when the window is closed; to provide means within the house for unlatching the lock; to provide means for opening the window when the latch is unlatched and to generally improve and 20 simplify locks of this character.

With these objects in view the invention consists in the novel construction and arrangement of parts, hereinafter described, illustrated in the accompanying drawings, 25 and particularly pointed out in the appended claims, it being understood that various changes in the form, proportions, size and minor details of construction may be made within the scope of the appended claims, 30 without departing from the spirit or sacrificing any of the advantages of the invention.

The invention thus set forth in general terms is illustrated in the accompanying 35 drawings forming part hereof, in which—

Figure 1 is a front elevation of a window showing the lock applied thereto.

Fig. 2 is a side elevation of the lock partly in section.

Fig. 3 is a transverse sectional view of the 40 lock.

Fig. 4 is a detail perspective view of the cover plate of the lock.

Fig. 5 is a detail perspective view of the 45 lock casing, and

Fig. 6 is a detail perspective view of the sliding latch member.

A practical embodiment of the invention is disclosed in the accompanying drawings, 50 forming a part of this specification in which similar numerals of reference indicate corresponding parts throughout the several views.

The sash 1 of a window such as is ordinarily used in cellars is shown hinged in the

usual manner at 2 to the frame 3, the sash 1 carrying at its free or swinging edge a bar 4 arranged to engage the lock as will be hereinafter described.

The lock comprises three principal parts, 60 the casing 5 best illustrated in Fig. 5, the sliding latch member 6 shown in Fig. 6 and the cover plate 7 illustrated in Fig. 4. The casing 5 is mounted in a suitable socket 8 formed in the window frame 3, the sliding 65 latch member being slidably mounted within said casing, the cover plate 7 retaining the latch member within the casing. The cover and casing are permanently attached to the the window frame by means of screws 9 70 or their equivalents.

The sliding latch member 6 is of channel shape in cross section and comprises the back portion 10 having a lip 11 at its upper extremity, the flange 12 and the flange 13 75 which latter flange is provided at its upper and lower ends respectively with the ears 14 and 15 arranged to be slidably protruded through the elongated slot 16 formed in the cover plate.

The ear 14 is provided with the downwardly and rearwardly inclined lower edge 17 terminating in the upwardly disposed recess 18 and the ear 15 is provided with the upwardly and rearwardly inclined upper edge 19. A coil spring 20 is connected at its upper end to the lip 11 upon the sliding latch member and at its lower end to the pin 21 upon the cover plate 7 normally holding the sliding latch member in position 80 shown in Fig. 2, the bar 4 upon the window sash being retained within the recess 18 in the ear 14 normally holding the window locked in the closed position.

For the purpose of unlocking the device 95 from the interior of the house a wire or other flexible member 22 is attached through a suitable aperture 23 in the sliding latch member, this wire being connected at its upper end to a substantially horizontally disposed wire 24 connected at one end as shown at 25 to any suitable portion of the wall or ceiling of the cellar, the other end thereof extending some considerable distance from the wire 22 and being connected as shown 100 at 26 at any convenient point.

When it is desired to open the window the wire 24 is grasped at a place near the connecting point 26 and a pull upon the wire will raise the sliding latch member 6 110

causing the bar 4 to be pushed away from the latch member as it rides upon the inclined face 19.

When the window is closed the upper edge 5 of the bar 4 will engage the downwardly inclined under edge of the ear 14, sliding the catch member upwardly against the pull of the spring until the bar passes beyond the lower end of the edge 17 when the spring 10 will draw the catch member down seating the bar 12 in the recess 8 locking the window.

I claim:—

1. A lock for a hinged window including a hinged casing mounted upon the window 15 frame, a channel shaped sliding latch member mounted therein and provided with a pair of outwardly tapered ears and with a recess, the casing being provided with a slot through which said ears protrude, a bar 20 carried by the window sash and arranged to be received between the ears and means for normally holding the recess in engagement with the bar.

2. A lock for a hinged window including 25 a hinged casing mounted upon the window frame, a channel shaped sliding latch member mounted therein and provided with a pair of outwardly tapered ears and with a recess, the casing being provided with a slot 30 through which said ears protrude, a bar carried by the window sash and arranged to be received between the ears, and a coil spring located within the channel shaped latch member and connecting the latch mem-

ber and casing to normally hold the recess 35 in engagement with the bar.

3. A lock for a hinged window including a hinged casing mounted upon the window frame, a channel shaped sliding latch member mounted therein and provided with a 40 pair of outwardly tapered ears and with a recess, the casing being provided with a slot through which said ears protrude, a bar carried by the window sash and arranged to be received between the ears and means for 45 normally holding the recess in engagement with the bar and means for sliding the latch member to throw the recess out of engagement with the bar.

4. A lock for a hinged window including 50 a hinged casing mounted upon the window frame, a channel shaped sliding latch member mounted therein and provided with a pair of outwardly tapered ears and with a recess, the casing being provided with a slot 55 through which said ears protrude, a bar carried by the window sash and arranged to be received between the ears, and a coil spring located within the channel shaped latch member and connecting the latch member 60 and casing to normally hold the recess in engagement with the bar, and means for sliding the latch member against the action of the spring to throw the bar out of the recess.

In testimony that I claim the above I 65 have hereunto subscribed my name.

FREDERICK HALDEMAN.
